UNITED STATES PATENT OFFICE

KARL M. HAMILTON, OF CHICAGO, ILLINOIS, ASSIGNOR TO THE BETTENDORF COMPANY, OF BETTENDORF, IOWA, A CORPORATION OF IOWA

CAR TRUCK

Application filed November 27, 1929. Serial No. 410,054.

My invention relates to improvements on car trucks, and more particularly to car trucks of the swing motion type.

An object of my invention is to provide an efficient, strong and durable swing motion truck wherein the spring plank consists of a casting supported from the transom by swing links to provide for lateral or side motion, and having spring seats and spring 10 plank bearings formed at its ends.

Another object of the invention is to provide an improved spring plank, with which is combined the spring seats and spring plank bearings in one single unit capable of being 15 cast as a single piece, thereby eliminating the handling and assembling of numerous parts and reducing the cost of manufacture.

Another object is to provide, in a structure as above indicated, simple means for 20 adjusting the height of the springs which support the bolster to compensate for set in the springs or for variations that may occur in manufacture.

Other objects of my invention will appear 25 hereinafter.

In the accompanying drawings,

Fig. 1 is a top plan view of a portion of a truck embodying my invention, the guide columns of the side frame being shown in section and the bolster being partly broken away 30 to show the parts beneath;

Fig. 2 is a transverse vertical section approximately on the line 2—2 of Fig. 1;

Fig. 3 is a top plan of the spring plank 35 casting showing a spring seat and spring plank bearing formed at the end thereof;

Fig. 4 is a vertical section on the line 4—4 of Fig. 3;

Fig. 5 is a perspective view of the spring 40 plank structure shown in Fig. 3; and

Fig. 6 is a detail perspective of an adjustment shim.

I have not deemed it necessary to illustrate in the drawings a complete truck, since the 45 parts shown clearly illustrate the invention. It is understood that the other side of the truck is similar to that shown in the drawings.

In the structure illustrated, the reference 50 character A refers generally to the side

frame. The transom casting is indicated generally at B, the bolster at C, the elliptic springs at D, and the spring plank casting at E.

The side frame may be of the usual integral 55 cast type having an integral upper arch bar 10 and a lower arch bar 11 of channeled or U-shaped construction, and having the vertically disposed guide columns 13 centrally positioned with respect to the journal ends of 60 the side frame and spaced apart to form, in conjunction with the upper and lower arch bars, a substantially rectangular window opening within which the end of the transom B is positioned. 65

The transom casting B comprises two substantially horizontally disposed channeled beams 12—12, which extend from side frame to side frame of the truck. These beams are spaced apart and are substantially parallel 70 at their end portions and diverge from these end portions to the central line of the structure. The end sections of the transom which fit within the openings in the side frames are integrally formed at the ends of the beams. 75 They comprise the top cross connecting members 14, bottom cross connecting members 15, and the two upright side members 16, all integrally formed at the ends of the beams. The bottom members 15 rest directly upon 80 the upper surfaces 17 of the lower arch bars, and have, Fig. 2, hollow bosses 18 which extend down between the flanges of the lower arch bars to interlock the side frames and transom against displacement. 85

The relative height of the window openings in the side frames, and the rectangular end sections of the transom, is such that the end sections can be inserted into the window openings and then dropped down to interlock 90 the bosses 18 with the lower arch bars. At the end portions of the transom beams where they join the end sections, shoulders 19 are provided which bear against the inner edges of the guide columns 13 to prevent tilting 95 of the side frames.

The bolster C may be of any suitable type for use in connection with lateral motion trucks. It is provided with the usual center plate 20 and side bearing seats 21 on its top 100

side. The ends of the bolster bear upon the upper members of full elliptic springs D which extend crosswise of the truck and transverse to the longitudinal plane of the side frames, the springs extending through the hollow end sections of the transom and beyond the side frames. The ends of the bolster have downwardly extending lugs 22 on each side of the springs to straddle the springs and prevent relative displacement of the springs and bolster. The lugs on each side of the bolster are spaced apart forming recesses 23 to accommodate the spring bands 24 which bind the leaves of the springs together.

15 The spring plank E extends transversely of the truck beneath the transom and bolster, and is suspended at its ends from the transom through the medium of the parallel suspension links 25. A pair of these links are 20 provided at each end of the structure and the links of each pair are disposed at the sides of the spring plank. The upper ends of the links pass upwardly through suitable slots or openings 26 in the transom beams 25 and are pivotally connected to the transom beams by the pivot pins 27 resting in suitable bearings formed in the transom beams. The lower ends of the links of each pair carry a key member 28 which supports the end of 30 the spring plank E.

The spring plank E, in the present structure, is made in the form of an integral casting of channel construction and having a flat body portion 30 with integral, upstanding flanges 31 along its edges and extending from end to end. The end portions of the side flanges are widened to form end members 32 between which the spring seats 33 are formed. The end members 32 have in-standing lugs 34 spaced apart to form recesses 35 which accommodate the spring bands 36 and which serve as an interlocking connection between the springs and spring seats to prevent relative displacement of 40 these parts. The spring seat is positioned above the flat body portion 30 a suitable distance for the purpose, and an integral transverse rib 37 is formed between the body portion 30 and the spring seat to strengthen the 45 structure and support the spring seat. Integral intermediate ribs 38 are also provided between the spring seat and the plank portion to further strengthen the structure.

Spring plank bearings are positioned below the body portion and are integrally formed at the lower ends of the end members 32. In the present structure, these bearings are formed as inverted U-shaped members 39 having bearing recesses 40 axially disposed transversely of the length of the body portion and resting upon the keys 28. Transverse vertical ribs 41, aligned with the ribs 37, are formed between the body portion 30 of the bearing member 39. Integral intermediate ribs 42 are also provided between the

under side of the body portion and the bearing members 39 and are preferably vertically aligned with the corresponding intermediate ribs 38. The ends 39' of the bearing members extend beyond the end members 32 to conform to the space between the suspension links, and these extended portions 39 are braced by integral diagonal ribs 43. The spring seats, spring plank bearings and the spring plank are all formed integrally as a single casting, which is strong and substantial, capable of withstanding all of the strains to which a structure of this character is subjected, and capable of being manufactured as a unit. This unitary construction eliminates the handling and assembling of a number of individual pieces and the danger of these individual pieces becoming accidentally displaced and lost.

It is desirable that the height of the springs be capable of adjustment to compensate for set of the springs or variations in the manufacture of the parts. This adjustment is provided for by the simple expedient of shims positioned between the spring seats and the springs. The shims may be in the form of flat plates 45 of the required thickness, such as illustrated in Figs. 4 and 6. They can be positioned between the lower spring bands 36 and the spring seats. They are made long enough to extend from side to side with their ends in the recesses 35, so that they will be held against displacement by the lugs 34.

I am aware that changes in the construction and arrangement of the parts may be made without departing from the spirit of the invention, and I hereby reserve the right to make such changes as fairly fall within the scope of the appended claims.

I claim:

1. In a car truck, the combination of a side frame, a transom supported thereby, a bolster, a spring plank, means suspending the spring plank from said transom, a spring between the bolster and spring plank, a seat for said spring formed integrally with said spring plank, a bearing member positioned below said spring plank and bearing upon said suspension means, and integral means connecting said bearing with said spring plank.

2. In a car truck, the combination of a side frame and a transom mounted thereon, suspension means on said transom for supporting a spring plank, a spring plank having a bearing spaced below said spring plank and engaging said suspension means, a spring seat spaced above said spring plank, and integral spacing elements between the bearing and spring plank and between the spring seat and spring plank.

3. As an article of manufacture, a cast spring plank for car trucks, said spring plank comprising an elongated body having integral spring seat members on its upper side adja-

cent its ends, bearing members below its under side, and integral reinforcing elements between and connected with the bearings and spring plank body.

5. As an article of manufacture, an integral spring plank unit for car trucks, comprising an elongated beam casting having a spring supporting plate integrally formed at its end portion and spaced above the body of the 10 plank, and integral spring retaining lugs upstanding from said plate at the sides thereof.

6. As an article of manufacture, an integral spring plank unit for car trucks, comprising an elongated beam casting having a spring 15 supporting plate integrally formed at its end portion and spaced above said beam, and a depending bearing integrally formed with and spaced below said beam.

7. A spring plank for car trucks, comprising a body member, a spring supporting seat member at its end, integral ribs spacing the seat member above the body member, and integral lugs upstanding from said seat member at the sides thereof.

25. 8. A spring plank for car trucks, comprising a body member having side flanges adjacent its end, a spring seat member positioned between and connected with said flanges, and spring retaining lugs integral with said flanges and extending above said seat member.

9. A spring plank for car trucks comprising a body member having downwardly extending side flanges, and a bearing member connected to said flanges below the body and 40 having its axis disposed transversely to the length of the body member.

10. A spring plank for car trucks comprising a body member having downwardly extending side flanges, a bearing member connected to said flanges and having its axis disposed transversely to the length of the body member, and intermediate ribs extending between and connected to said body member and said bearing member.

50. 11. As an article of manufacture, an integral spring plank unit for car trucks, comprising an elongated beam casting having integral extensions formed on its under side adjacent its ends, and integral bearings formed 55 with said extensions and spaced from the beam casting thereby.

12. As an article of manufacture, an integral spring plank unit for car trucks, comprising an elongated beam casting having a spring supporting plate portion integrally formed adjacent each end on its upper side, and a depending bearing integrally formed with and spaced below said beam.

65. 13. As an article of manufacture, an integral spring plank unit for car trucks, com-

prising an elongated beam casting having a bearing integrally formed on its under side adjacent each end, a spring supporting plate integrally formed adjacent each end portion and spaced above said beam, and side flanges 70 integral with said beam casting, bearing and plate, and extending above said plate.

14. In a one-piece spring plank for railway trucks, the combination of a spring plank body, a spring seat member positioned above 75 said body and integrally connected therewith adjacent the end, a bearing member spaced below said body, integral flanges at the side of said body having upward extensions integrally connected with the seat member and 80 extending thereabove, and downward extensions integrally connected with said bearing.

In witness that I claim the foregoing I have hereunto subscribed my name this 2nd 85 day of November, 1929.

KARL M. HAMILTON.
